UNITED STATES PATENT OFFICE

2,196,074

WALL STRUCTURE AND BUILDING BLOCK
THEREFORGeorge D. King, Chicago, Ill., assignor to United
States Gypsum Company, Chicago, Ill., a cor-
poration of Illinois

Application February 28, 1938, Serial No. 192,929

17 Claims. (Cl. 72—42)

This invention relates to cellular wall structure and building block therefor, and more particularly to a light-transmitting wall comprising a cellular frame-like load-supporting portion having closely adjacent individual transverse cells therethrough with comparatively thin partitions therebetween and light-transmitting facings covering the open sides of the frame or shell whereby each cell provides a comparatively small individual "dead air" space to provide effective heat insulation and to enable light transmission completely through the wall.

It is an object of the invention to provide a wall of the character described in which the component parts are so constructed and arranged as to enable only restricted so-called "breathing" of individual cells through one side of the wall while preventing breathing and the infiltration of moisture or water vapor through the opposite side of the wall and preferably also preventing moisture infiltration between cells.

Wherever the term "breathing" is used in the specification or claims as descriptive of a characteristic of the invention disclosed herein, it is intended to mean that only restricted breathing may take place, such breathing being only sufficient to enable the maintenance of a moisture content within the block substantially corresponding to the moisture content of the air on the outside of the wall. This is accomplished by diffusion and infiltration which is not sufficient to permit rapid changes of air such as ordinarily termed convection currents.

The invention further contemplates a light-transmitting wall structure comprising individual units or blocks preferably secured together with mortar and each having one or more hollow spaces or cells therein through which light may be transmitted, and which are so constructed and arranged that one side of the wall may be substantially impervious to moisture and water vapor and the opposite side will enable breathing of the hollow space in each individual unit.

The invention is particularly applicable to load-supporting blocks and walls constructed thereof; however, it is not limited thereto, as it is applicable to other types of hollow blocks, such, for instance, as all-glass blocks having light-transmitting sides whereby light may be transmitted completely therethrough.

More specifically, the invention comprehends a load-supporting building block in which substantially the entire load is supported by a hollow shell having open sides and comparatively thick walls which are preferably substantially

impervious to air, moisture, and water vapor and in which the open sides of the shell are closed by means of light-transmitting plates or so-called facings. The facing on one side of each shell is sealed thereto in a manner to prevent breathing from one side of a wall in which the blocks are used, and the facing on the opposite side of the shell is so constructed or so attached that so-called breathing may take place. The ports or holes in the facing of the shell through which the breathing takes place may be so constructed that air and moisture vapor may pass into and out of the shell without material convection currents being set up, as will be hereinafter more specifically described.

In practice it has been found that in cold weather any moisture present in the hollow space within a light-transmitting building block will have a tendency to condense on the interior surface of the cover plate or facing adjacent the cold side of the wall and may even form a frost coating. This is true even with all-glass blocks which are sealed under a vacuum or at least under less than atmospheric pressure. This condensation decreases light transmission, gives an unclean appearance to the block, and creates the impression to an observer that the block is defective.

The present invention contemplates a load-bearing and light-transmitting block wherein one side of the block may permit breathing therethrough in such a manner that condensation on the inside of the exposed face is materially decreased or entirely eliminated.

It is a further object to provide a wall structure comprising a plurality of superimposed hollow blocks having light-transmitting facings wherein the wall and the component parts are arranged to enable moisture diffusion from the hollow space in each block through the outer surface of said wall without permitting heat loss by convection currents to an appreciable extent. The heat-insulating value of the so-called "dead air" space is, therefore, not materially decreased.

This invention is an improvement over the usual type of hollow building blocks which may or may not be light-transmitting, and particularly is an improvement over light-transmitting blocks of the type disclosed in the copending application of George D. King and George L. Phelps, Serial No. 185,825, filed January 20, 1938.

In the above-noted application a building block is provided which comprises a hollow shell formed of plastic material such as gypsum or

other suitable cement or aggregate. Other suitable materials may be used, such as Portland cement, terra cotta, burned clay, metal, processed wood, or other material which may be cast or otherwise formed into hollow shells by the usual well known methods. These hollow shells are preferably pressure molded and may be provided with moisture and moisture-vapor proof characteristics either by incorporating 10 waterproofing material with the base material from which the shells are formed or by suitably coating or impregnating the shell in such a manner that substantially the entire surface is moisture and water-vapor proof. Light-transmitting 15 plates or facings, such as glass or other suitable material, are sealed to the side walls of the shell in a manner to close the openings therein and to enable relative contraction and expansion of the component parts without destroying the effectiveness of the seal. The light-transmitting plates are inherently impervious to air and moisture in any form. Therefore, the completed hollow block is effectively sealed against air and moisture or water-vapor infiltration. It has 20 been found, however, that in blocks of this type some condensation may take place on the inner surface of the outside facing. It is, therefore, an object of the present invention to provide means whereby this condensation may be substantially eliminated and the light-transmitting characteristics of the block will be unimpaired and a wall constructed of such blocks will enable light to be transmitted completely 25 throughout.

35 Further objects will be apparent from the specification and the appended claims.

In the drawing:

Figure 1 is a perspective view of a rectangular block partly broken away and illustrates one embodiment of the invention.

40 Fig. 2 is a perspective view of a block somewhat similar to that shown in Fig. 1, but elongated and provided with a transverse partition for the purpose of providing greater load-bearing strength.

45 Fig. 3 is a transverse sectional view taken on a line substantially corresponding to line 3—3 of Fig. 2 and illustrates one method of securing the side plates and providing breathing characteristics.

50 Fig. 4 is a diagrammatic view illustrating the blocks in position in a wall with the usual mortar therebetween.

Fig. 5 is a fragmentary sectional view similar 55 to Fig. 3 but illustrates a slightly different means to enable breathing through the outer surface of the wall.

Fig. 6 is a front view of the embodiment illustrated in Fig. 5.

60 Fig. 7 is a transverse sectional view similar to Fig. 3, but illustrates a slightly different method of securing the front light-transmitting plate whereby breathing is permitted.

Fig. 8 is a fragmentary view illustrating another method of mounting the plates and providing for breathing.

Fig. 9 is a perspective view of an all-glass block with a portion broken away and illustrates one embodiment of the invention.

70 Fig. 10 is an enlarged detail section through the light-transmitting portion of a block and illustrates a method of providing a filter in a breather opening.

75 Referring to the drawing in detail, the embodiment illustrated in Figs. 1 and 4 comprises

a rectangular hollow shell 1 having comparatively thick walls and open sides as illustrated, the rear open side being covered by means of a light-transmitting plate or facing 2 which may be of glass or other suitable material and the front side being covered by means of a similar light-transmitting facing 3. By this construction it will be apparent that light may be transmitted completely through the block and therefore through a wall in which the blocks are incorporated.

The shell 1 is preferably pressure molded or otherwise formed of gypsum or a suitable cement or aggregate. Other suitable materials may be used to provide the necessary strength 15 and may be such as to provide suitable moisture-proof characteristics, or the shells may be entirely coated with suitable moisture and water-vapor proofing material. In any event, the shell is of suitable material and so constructed as to provide a unit capable of supporting a substantial load and preferably capable of bonding with conventional mortars. An efficient reinforcing means, such as expanded metal 4, may be embedded within the material of the 20 block as illustrated in Fig. 3.

In cases where the material of the block is not inherently moisture and water-vapor proof, the entire inner and outer surfaces of the shell may be coated with suitable waterproofing material to prevent moisture or vapor infiltration. The light-transmitting facings 3 may be secured in position by a layer of suitable adhesive material 5 (Figs. 1 and 2) applied between the facings and the walls of the shell. This adhesive 5 is preferably a yieldable material such as an asphalt adhesive and therefore permits a differential contraction and expansion of the shell and facings in response to temperature changes.

The shell may be formed with an annular 40 groove or depression 6 therein, as shown particularly in Figs. 1 and 4, which provides a pocket between adjacent blocks in a wall. This pocket may be completely filled with mortar 7 (Fig. 4). When this groove or pocket is used, 45 the outer edges of the block may be substantially in contact as shown and the visible mortar joint between the facings is thereby reduced to a minimum.

The facings 2 and 3 are somewhat smaller than 50 the sides of the block so that substantially the entire load is supported by the shells. The walls of the block are preferably somewhat thinner adjacent the edges than in the middle (Fig. 4), thereby reducing to a minimum the non-light-transmitting areas of the block.

The outer surface of the shell may be provided with a moisture and vapor proof coating 8 (Fig. 3) and the facings may be secured and sealed to the walls by means of a layer of flexible adhesive 9 therebetween. This adhesive may be of material similar to the coating 8 or any other suitable flexible material such as adhesive 5, whereby relative expansion and contraction may take place without injury to the blocks and 60 whereby the shell will not be broken. It will be understood, of course, that the embodiment shown in Fig. 2 may also be provided with an annular groove similar to the groove 6 if desired. In this embodiment the elongated block 70 1* may be provided with one or more transverse partitions 10, which provide air cells of a predetermined size and contribute additional load-supporting strength.

As previously stated, the facings and the shell 75

are impervious to moisture and water vapor, particularly after the block has been completely assembled, and the rear facing is so attached to the shell that moisture or water vapor cannot 5 infiltrate into the hollow block through the shell or the rear facing or therebetween.

In the present invention, the front facing 3 may also be completely sealed to the block as described. However, means is provided where- 10 by so-called breathing may take place on that side of the block normally exposed to low temperature. When the blocks are assembled in a building structure the breathing side should face a live air space or a space to which a large volume of air is permitted to flow.

In the embodiment illustrated in Figs. 1 to 4, inclusive, a plurality of small perforations or slits 11 are provided through the facing 3, one or more of the perforations preferably being positioned adjacent the bottom of the block, as shown, and one or more similar perforations 11^a being positioned adjacent the top of the block and communicating with the hollow space therein. The perforations are preferably angularly disposed, as illustrated, in order to prevent water entering therein. It will be understood that it is not essential that the perforations should be in the positions shown nor that they should be angularly disposed. In any event, a sufficient number of perforations are provided and so distributed as to provide for so-called breathing through the front facing 3. The perforations are very small, preferably about one-sixteenth inch in diameter, and so disposed through the 35 facing as to enable the diffusion of moisture therethrough without the formation of convection currents sufficient to materially reduce the insulating characteristics of the so-called dead air space within the block. In other words, the 40 perforations are so formed and arranged and are of such number as to maintain by diffusion substantially the same moisture concentration within the hollow space as on the outside. For instance, in a block ten inches square, a perforation one-sixteenth inch in diameter placed near each corner will generally be sufficient. The moisture consequently diffuses in and out of the block without any substantial amount of convection current formation within the block. 45 The dead air space within the block is thereby substantially undisturbed, even though perforations are present, and the insulating value of the air space is substantially unimpaired.

In the embodiment illustrated in Figs. 5 and 6, the facing is not perforated. Instead, a small angular sheet metal member 12 is provided and inserted between the facing and the block, as shown, and is retained in position by means of the adhesive by which the facing is secured. The member 12 is formed to provide a very small duct 13 between the facing and the block, and these members 12 may be distributed around the edges of the facing as desired. It will be apparent that, in this embodiment, breathing may take 60 place in the same manner as previously described.

Fig. 7 illustrates another method by which breathing may be accomplished. In this embodiment the facings are provided with openings 14 to receive screws 15, by which the facings 70 may be secured to the shells. Sockets 16 may be embedded in the shells to receive the screws. In this embodiment the edges of the shells may be cut away to form a channel 17 communicating with the holes 14 in the facings. The screws 75 are preferably provided with a washer 18 and,

if desired, this washer may be corrugated, air porous, or otherwise formed to provide a breathing outlet.

Fig. 8 illustrates another embodiment in which the shell 1 is covered with a sheet metal covering 19. This covering extends outwardly beyond the edges of the block, as illustrated, and is provided with a downwardly extending flange 20, and the glass is retained against this flange by rolling or pressing an outer flange or lug 21 from 10 the dotted line position to the position against the glass, as shown. The sheet metal member 19 is provided with a suitable number of small perforations 22, whereby breathing may be accomplished.

Fig. 9 shows one embodiment of the invention comprising a hollow block having light-transmitting sides. In this embodiment the entire block 1^b may be of non-porous material such as glass and one side only may be perforated as 20 indicated at 11^b in order to enable breathing of the hollow space. The perforations may be of suitable size and arrangement to enable breathing without detrimental convection currents.

Fig. 10 is an enlarged sectional view through 25 one of the breather openings and illustrates a method of providing a porous filter in the wall of a block which filter will enable moisture diffusion through one surface of a wall and effectively prevent convection currents. The filters 30 may, of course, be placed in suitable locations to enable breathing of the individual blocks or through the outer surface of the wall as previously described.

In the embodiment illustrated, a suitable opening 23 may be provided through one of the light transparent facings 3 and this opening may be of any suitable size and shape as required. A breathing filter 24 may be inserted in the opening 23 and may consist of any suitable filtering 35 material such as a porous ceramic body which may be fused into place as shown or the porous body may be adhesively or otherwise suitably secured. These filter portions may be distributed in accordance with filtering requirements, and it 40 will be understood, of course, that the openings 11 may be closed by similar filtering plugs if desired. These filters may comprise sintered glass, unglazed porcelain, or similar porous material which will enable so-called breathing and moisture diffusion therethrough and at the same time effectively prevent the formation of convection currents.

It will be understood that small plugs or areas of porous filtering material such as first described 55 may be provided in place of the perforations 11^b shown in Fig. 9.

Modifications may be made without departing from the spirit of the invention, and it is therefore desired that the invention be limited only 60 by the prior art and the scope of the appended claims.

Having thus described this invention, what is claimed and desired to be secured by Letters Patent is:

1. A light-transmitting wall structure comprising cellular frame-like load-supporting portion having closely adjacent transverse cells therethrough with comparatively thin partitions therebetween, and light-transmitting facings 70 closing the open ends of said cells, said frame and one side of said wall being substantially moisture and water-vapor proof, the opposite side of said wall being moisture permeable sufficiently to enable diffusion therethrough while substan- 75

5 tally preventing convection currents sufficient to materially reduce the heat insulating characteristics of the air spaces.

6 2. A light-transmitting wall structure comprising a cellular frame-like load-supporting portion having closely adjacent transverse cells therethrough with comparatively thin partitions therebetween, and light-transmitting facings closing the open ends of said cells in non-load-bearing relation to each other and to said load-bearing portion, means sealing the facings to said load-bearing portion in a manner to prevent moisture or water-vapor infiltration therewith, the facings on one side of said wall being 10 moisture permeable only sufficiently to enable diffusion therethrough without material convection.

15 3. A light-transmitting wall structure comprising a cellular frame-like load-supporting portion having closely adjacent transverse cells therethrough with comparatively thin partitions therebetween, and light-transmitting facings closing the open ends of said cells in non-load-bearing relation to each other and to said load-bearing portion, means sealing the facings to said load-bearing portion in a manner to prevent moisture or water-vapor infiltration therewith, said sealing means being sufficiently flexible to enable relative expansion and contraction 20 therebetween in response to temperature changes, the facings on one side of said wall being moisture permeable only sufficiently to enable diffusion therethrough without material convection.

25 4. In a light-transmitting wall structure, a cellular load support comprising comparatively thin vertical and horizontal intersecting partitions forming closely adjacent cells, light-transmitting facings covering the open ends of said cells in non-load-bearing relation to said load-bearing portion and to each other, the facings on one side of said wall being sealed to said support and forming therewith a substantial barrier against the infiltration of moisture or water vapor through said wall, the opposite side of said 30 wall being permeable by moisture and substantially preventing convection currents.

35 5. A wall structure comprising a plurality of superimposed hollow blocks having light-transmitting facings, the outer sides of said blocks having perforations of appropriate size to enable breathing of the hollow space therein and substantially prevent convection.

40 6. A wall structure comprising a plurality of superimposed hollow blocks having light-transmitting facings, the outer facings of said blocks having perforations of appropriate size to enable breathing of the hollow spaces without excessive convection, said perforations being angularly disposed to prevent flow of liquid moisture into 45 said hollow spaces.

45 7. A light-transmitting wall structure for heated buildings comprising wall-forming hollow building blocks having light-transmitting sides, means securing said blocks together to form a substantially non-air-porous wall, the outer sides of said blocks being air porous.

50 8. In a building block, the combination with a load-supporting hollow shell having at least one open side, all of said shell, including one closed side, being sealed against the infiltration of air and moisture therethrough, with means closing the opposite side, said means having structural characteristics enabling moisture to be diffused therethrough and substantially preventing convection.

55 9. In a building block having a dead air space, the combination with a hollow load-supporting shell having open sides and comprising plastic material impervious to air and moisture and moisture vapor, of a light-transmitting facing sealed to one side of said shell to prevent air and moisture infiltration to the hollow space, and a light-transmitting facing secured to the opposite side, said last facing having small perforations therethrough of sufficient size to enable diffusion therethrough without the formation of convection currents sufficient to materially reduce the heat insulating characteristics of said dead air space.

60 10. In a load-bearing, light-transmitting block, the combination with an air and moisture impervious shell having open sides of light-transmitting plates sealing said open sides, one side of said block being provided with passageways sufficiently small to enable air and moisture infiltration therethrough while preventing convection.

65 11. A hollow building block of moisture impermeable material and having light-transmitting faces covering the hollow space, one side only of said block having ducts leading from said hollow space and sufficiently small to enable moisture diffusion from said hollow space and to substantially prevent convection.

70 12. A moisture proof building block comprising a load-bearing shell having open sides and comparatively thin walls, a light-transmitting facing sealed to one side of said shell to prevent moisture infiltration therethrough, and a light-transmitting facing secured to the opposite side of said shell, said facings being supported in non-load-bearing relation to said shell, the last mentioned side of said block being provided with one or more perforations therethrough of a size to enable breathing without material convection currents.

75 13. A hollow building block comprising a moisture proof shell having open sides, a moisture proof light-transmitting facing attached to each open side, a moisture proof seal between said moisture proof facing and said shell, and means providing an air duct from the hollow space in 40 said block and between said block and said facing.

80 14. A hollow building block comprising a substantially moisture proof shell having open sides, and a moisture proof light-transmitting closure 50 covering each open side, a restricted portion of the closure on one side comprising a cellular material having the filtering characteristics of unglazed porcelain or the like.

85 15. A hollow building block having light-transmitting sides, and one or more restricted areas of one side comprising porous filtering material having filtering characteristics comparable to unglazed porcelain or the like whereby moisture or moisture vapor may pass therethrough while substantially preventing detrimental convection currents.

90 16. A hollow building block comprising a shell of non-porous material, one side only of said block having spaced restricted areas of porous material having the filtering characteristics of sintered glass or the like.

95 17. A wall structure comprising a plurality of superimposed hollow blocks having light-transmitting facings, one of said facings being substantially impervious to air and moisture, the other facing having portions sufficiently porous to enable moisture infiltration and diffusion therethrough while preventing material convection.

GEORGE D. KING. 75
